POWER UNIT FOR A BLENDER OR THE LIKE

Carroll M. Gantz, North Canton, and John C. Harmon,
Parma, Ohio, assignors to The Hoover Company, North
Canton, Ohio, a corporation of Ohio

Filed Aug. 4, 1965, Ser. No. 86,432

Term of patent 14 years

(Cl. D89—1)

Fig. 1

Fig. 2

Fig. 3

Fig. 4

FIGURE 1 is a perspective view of a power unit for a blender or the like showing our new design;
FIGURE 2 is a side elevational view;
FIGURE 3 is a top plan view; and
FIGURE 4 is a rear elevational view.

The dominant features of our design reside in the portions shown in full lines.

We claim:

The ornamental design for a power unit housing for a blender or the like, substantially as shown and described.
